UNITED STATES PATENT OFFICE.

JOHN A. FRAZIER, OF GEORGESVILLE, ASSIGNOR OF ONE-HALF TO ISAAC MOORE, OF HARRISBURG, OHIO.

CAR-COUPING.

SPECIFICATION forming part of Letters Patent No. 365,807, dated July 5, 1887.

Application filed July 14, 1886. Serial No. 207,968. (No model.)

To all whom it may concern:

Be it known that I, JOHN A. FRAZIER, a citizen of the United States, residing at Georgesville, in the county of Franklin and 5 State of Ohio, have invented a certain new and useful Improvement in Car-Couplings; of which the following is a specification.

My invention relates to improvements in devices for coupling cars automatically, and 10 particularly relates to improvements on my former invention for which Letters Patent No. 267,868 were issued November 21, 1882.

The objects of my invention are, first, to so construct the coupling-hook of the spring- 15 actuated cap-plate as to form a coupling with an ordinary coupling-link; second, to admit of the use of an ordinary coupling-pin in case it is so desired; third, to so pivot the cap-plate within the draw-bar as to enable the 20 same to withstand a greater strain; fourth, to prevent any lateral strain on the operating-lever by so connecting said lever with its bearing on the cap-plate as to admit of the usual slight backward and forward movement of the 25 said cap without moving the lever from its original position. These objects I accomplish in the manner illustrated in the accompanying drawings, in which—

Figure 1 represents a longitudinal vertical 30 section of the draw-bar, showing its cap in elevation. Fig. 2 is an end view of the draw-bar. Fig. 3 is a longitudinal section of the cap-plate. Fig. 4 is a transverse section of the cap-plate, taken on the line $x-x$ of Fig. 1. Fig. 35 5 is a plan view of the draw-bar.

Similar letters refer to similar parts throughout the several views.

A represents a draw-bar, having, as shown in the above-mentioned patent, a longitudinal 40 recess from the top thereof, opening at the front end, and having a metallic cap-plate or coupling-tongue, G, pivoted within said recess by a pivot-bolt, k, made to pass transversely through the sides of the draw-bar and 45 through a downwardly-projecting shoulder of the cap G, near the bottom of the draw-bar. The rear end of the said cap is made to rest on a vertical coiled spring, F, seated in the rear end of the draw-bar recess and extending 50 within a short distance of the top thereof. From thence the cap-plate extends forward

until near the open flaring end of the draw-bar, and has its outer end formed slightly hook-shaped, as shown. At a point between the outer end of the cap-plate and its pivoted shoulder is provided a downwardly-projecting shoulder, H, which bears against a transverse stop-pin, I, made to extend between the side walls of the draw-bar, and which also acts as a rest for the cap when its hooked end is 60 inclined downward, as shown in Fig. 1 of the drawings. The head g of the cap plate has the surface of its outer end curved downwardly and inwardly, and a depression being formed in the bottom of the plate G immediately in rear of the said head, a short downwardly-projecting hook is thus formed, through the center of the lower edge of which is cut a shallow longitudinal notch or groove, K. The hooked cap-head g is provided with a central 65 vertical pin-hole, through which is made to pass a coupling-pin, L, having its upper projecting end screw-threaded to receive a nut thereon, and having its lower portion flanged forwardly at the point where it enters the notch K, said 70 flanged portion bearing against the inner surface of the notch and projecting slightly past the curved front of the hook g, from which point it extends downwardly and rearwardly 75 in a curved line to a point beneath the lower 80 side of the cap-hook g, forming a central continuation of the latter. The hooked end of the pin thus formed, when in its normal position, is made to rest in a hole in the bottom of the draw-bar, and the rear side of said hook 85 is provided with a slight inwardly-curved depression, to better form a bearing for the inner side of the end of the link. The open end of the draw-bar is provided with an inwardly-curved transverse cap guide-plate, M, having 90 a central vertical groove, m, on its inner side, and an upwardly-curved notch at the lower termination of said groove. This transverse plate extends across the upper portion of the draw-bar and has its inner surface curved to 95 conform to the curve of the cap-head g, against which it bears loosely. A rounded curved projection, g', extending downward and meeting the projecting flange of the pin L, is provided on the front end of the cap-head, thus 100 forming an upward continuation of the front line of the flange of the pin L. This projec-

tion g' is adapted to fit loosely within the central groove of the cap guide-plate M and slide therein when the cap is forced upward by the insertion of the end of the ordinary form of coupling-link. In case the pin L should, by accident or otherwise, become broken, the nut n may be removed from the pin-head and an ordinary coupling-pin may readily be inserted in the pin-hole in the cap. The inner surface 5 of the bottom of the draw-bar, immediately in the rear of the lower hooked end of the pin L, being slightly cut away, and a corresponding curved depression being made in the under side of the cap-plate, it will be seen that room 10 is allowed for such upward and downward play of the link as might be made necessary by the attachment to cars of uneven height or by the unevenness of the track. It will also be seen that, the pivot-bolt k being located 15 near the bottom of the recessed portion of the draw-bar, the bearing of the link against the pin-hook is on a level with said pivot-bolt, thus causing a direct strain thereon, and operating to prevent the cap-head and its pin 20 L from being forced upward by the pressure of the link. From the upper side of the cap-plate is made to project a lug, q, to which is loosely pivoted the lower end of a short block, 25

r, to the upper end of which is fixed one end of an operating-lever, v, which, extending laterally outward, has bearings projecting from the end of the car-frame, and has its outer end extended to form a handle. By downward pressure on this lever-handle the cap-plate having the coupling-pin thereon is raised, and the cars thus uncoupled. The block r being loosely pivoted to the lug q, it will readily be seen that the latter may be allowed a reasonable play backward and forward without disturbing the position of the lever. 30

Having now fully described my invention, what I claim, and desire to secure by Letters Patent, is—

The combination, with the recessed draw-bar, of the spring-actuated cap-plate G, pivoted within said recess, having detachably secured within a central pin-hole in the head thereof the pin L, and having the projection g' , adapted to slide within a groove in the bearing-plate M, substantially as and for the purpose specified. 40

JOHN A. FRAZIER.
